(57) CLAIM

I claim the ornamental design for the ring, as shown and described.

DESCRIPTION

FIG. 1 is a front perspective view of the new ornamental ring of the present invention.

FIG. 2 is a front view thereof.

FIG. 3 is a right side view of which the left side is a mirror image thereof.

FIG. 4 is a back view thereof; and,

FIG. 5 is a top plan view of which the bottom is a mirror image thereof.
